UNITED STATES PATENT OFFICE

2,675,041

CONSTRUCTION OF BRIEF CASES
OR THE LIKE

Jacob Wagner, Chicago, Ill.

Application May 29, 1952, Serial No. 290,715

4 Claims. (Cl. 150—1.6)

1

This invention relates to bags such as brief cases.

One object of this invention is to provide a steel-like spring, between the outer leather covering of a lock flap and the under covering thereof or with one end of said spring flap riveted to the metal frame of a brief case, travelling bag, valise or the like, and with the other end of said spring riveted to a metal hasp on the end of the said flap. Such construction provides a flap which will bend out of normal position and will automatically spring open, upon releasing the latch mechanism wherein said flap's hasp fits, and spring back to normal position.

Another object of this invention is to provide a device of the character hereinbefore mentioned which will prevent bending or warping of the metal frame to which the same is attached due to overstrain placed on the frame from excess weight therein.

Still another object of this invention is to provide a device as hereinbefore mentioned which will prevent bulging of the bag and undue distortion therefrom at the top portion of the outer walls of the bag to which the instant invention is attached.

Still another object of this invention is to provide a device as hereinbefore described which will automatically spring open the metal jaws, to which it is attached when the latch in which the flap's hasp fits, is unlocked.

Still another object of this invention is to provide a strong, durable spring-latch assembly of the character described, which shall be relatively inexpensive to use, easy to assemble and practical and efficient to a high degree in use.

Other objects of this invention will in part be obvious and in part hereinafter pointed out.

The invention accordingly consists in the features of construction, combination of elements, and arrangement of parts, which will be exemplified in the construction hereinafter described, and of which the scope of invention will be indicated in the following claims.

In the accompanying drawings in which is shown various illustrative embodiments of this invention:

Fig. 1 is a perspective view of a brief case, embodying the invention, and with parts therein cut away;

Fig. 2 is an enlarged cross-sectional view taken along line 2—2 of Fig. 1;

Fig. 3 is a view similar to Fig. 2, but showing the brief case with the flap extended; and

Fig. 4 is an enlarged transverse sectional view of the flap on the line 4—4.

2

Referring now in detail to the drawing, 10 designates a brief case of conventional construction, comprising front and rear leather panel walls 11 and 12 interconnected by expandable and contractible leather end walls 13 and 14 and bottom wall 15.

Attached to the top of the upper edges of the front and rear walls 11 and 12 is a conventional jaw type frame 15, comprising an inner lower U-shaped frame 16 and an outer or upper U-shaped frame 17. Said frame 16, is surrounded along its entire length by leather sheeting 18, secured to the top of front wall 11, by stitching 19. Said frame 17, is surrounded along its entire length by leather sheeting 20.

Interposed at one portion between said covered U-shaped frame 17 and rear wall 12, is a flap 22 having an end 21 and said leather sheeting 20 surrounding U-shaped frame 17, rear wall 12 and end 21 of flap 22 are secured together by stitching 23. Said covered U-shaped frames 16 and 17 overlap each other and are pivotally connected at their ends by rivet 24, it being understood that frames 16 and 17 are attached to said end walls 13 and 14 by their respective lines of stitching 19 and 23 in the manner described above.

Said flap comprising an outer leather wall 24a and an inner leather wall 25 and a steel spring 26 interposed between said walls 24a and 25. Said walls 24a and 25 being secured together at their outer edges by stitching 26a and being secured near end 21 of flap 22 together with interposed steel spring 26, underlying U-shaped frame 17, and portion 27 of leather sheeting 20, interposed between said frame 17 and wall 25, by rivet 28. A conventional hasp 29 being at the other end of flap 22 and surrounding the ends of walls 24a and 25, and being secured to said walls 24a, 25 and interposed steel strip 26 by rivet 30. A leather protector tab 31 being narrower than and underlying said flap 22, and said tab 31, leather sheeting 18 and interposed top of front wall, being secured by the said line of stitching.

Said hasp 29, having a keeper 32. A conventional latch mechanism 33 with conventional locking means 33a therein being secured to front wall 11 and being associated with said keeper 32.

Said brief case 10 comprising also a conventional handle 34 being of any desired shape or size and being attached to the outer frame 17, and conventional partition walls 35 and 36 longitudinally dividing the interior of brief case 10.

It will be noted that as pressure is applied to latch mechanism 33 to unlock the same, flap 22 due to the resilient spring action of member 26 automatically pulls the keeper 32 of the hasp 29

out of said lock mechanism 33 and springs back to its normal straight position, at the same time spreading the jaws 16 and 17 slightly apart so as to facilitate access to the interior of brief case 10.

It will be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention I claim as new and desire to secure by Letters Patent:

1. A bag, open at the top, and having a pair of pivoted jaws at the open top, said jaws comprising metallic members each having a top portion and downwardly extending arms with the lower ends of the arms of one jaw pivoted to the lower ends of the arms of the other jaw, a flap extending from the center of one jaw comprising top and bottom layers of flexible material, a spring member between said layers riveted at one end to the center of the top portion of one jaw, a hasp fixed to the free ends of said layers, the free end of said strip spring being riveted to said metal hasp, a latching device on said bag and including means to releasably engage the hasp.

2. In a carrying article comprising front and rear walls and expandible and contractible bellows-like ends, overlapping jaws pivoted at their ends, a flap secured to the overlying jaw and having a normal extended position in a plane disposed substantially normal to the plane of the jaw and comprising a resilient member therein and locking means at its free end, said resilient member overextending the front wall, a latch mechanism having a conventional lock on the front side of the carrying article, said flap being caused to bend out of said normal position to fit into a latch mechanism and being caused to automatically flip up into said normal position when said latch mechanism is put in unlatching position releasing the flap locking means positioned therein, and said flap comprising an outer and inner cover with said resilient member being interposed therein, said resilient member being of spring steel, and said covers being secured at their

edges, and said flap being secured to the overlying jaw by means of a rivet passing through said leather covers and said steel spring therein, and said lock mechanism at the free end of the flap comprising a hasp having a keeper thereon, said hasp being secured to said flap by means of a rivet passing through said hasp, covers and steel spring.

3. In an article carrying case comprising a body having an opening, a pair of metal members attached to the body on opposite sides of the opening and movable away from each other to extend the opening in the bag, means to lock the bag comprising a latch mechanism on the body, an overextending flap having a hasp thereon and a keeper on said hasp, said flap being attached to the body on one side of the opening and comprising a central spring member, said spring member being secured at one end to the hasp and attached at its other end to the metal member at said one side of said opening, and said keeper fitting into said latch mechanism.

4. A bag comprising a bottom wall, front and rear walls extending upwardly from the bottom wall, and end walls interconnecting said front and rear walls, a pair of interposed jaw frames attached to the upper ends of the front and rear walls and to the upper ends of the end walls, said jaws being adapted to be closed and opened, a flap connected at its upper end to the center of the jaw of the rear wall, and extending forwardly therefrom and comprising outer and inner walls, a hasp on the free end of said flap, a flat spring member interposed between the outer and inner walls of said flap and integrally secured at one end to the center of said rear jaw member of said bag, and the free end of said flap with said interposed steel spring being secured to said hasp, and means on the front wall of said bag to releasably engage said hasp, said flap being adapted to be automatically raised upon releasing the hasp.
